PULLING TOOL

Charles J. Piper, Washington, D. C.

Application July 28, 1944, Serial No. 547,082

1 Claim. (Cl. 29—261)

This invention relates to a tool designed principally for the extraction of ball bearings or the like from recesses or "blind" holes. Heretofore the extraction of ring-like devices from "blind" holes has been difficult and considerable time has been wasted in the performance of the operation.

It is the object of the present invention to provide a tool of this character which is simple and compact in construction and can be positioned readily within the recess or "blind" hole and the bearing or other object to be removed, it being possible thereafter to quickly adjust the tool so as to engage the bearing or other object, after which, by a further operation, the tool will act as a screw jack and forcibly remove the object to be withdrawn.

A still further object is to provide a tool which is inexpensive, can be conveniently carried, and will not readily get out of order.

With the foregoing and other objects in view, which will appear as the description proceeds, the invention resides in the combination and arrangement of parts and in the details of construction hereinafter described and claimed, it being understood that changes in the precise embodiment of the invention herein described, may be made within the scope of what is claimed, without departing from the spirit of the invention.

In the accompanying drawing the preferred form of the invention has been shown.

In said drawing

Figure 1 is a section through a recessed structure containing a ball bearing to be removed therefrom, the tool constituting the present invention being shown immediately following its insertion thereinto.

Figure 2 is a similar view showing the tool partially in section, after it has been adjusted to engage the bearing and after the bearing has been partially withdrawn.

Figure 3 is a section on line 3—3 of Figure 1.

Referring to the figures by characters of reference, 1 designates a crosshead having a screw thread opening 2 extending through the center thereof. The ends of the crosshead are forked as noted at 3 and extending across each of these forks is a pivot pin 4, on which is mounted a head 5 located at one end of an arm 6 constituting a jaw of the tool. The other end of the arm has a lug 7 extending laterally therefrom. The head 5 has a cam 8 extending from that end remote from arm 6, and this cam comprises two inclined faces 9 and 10 merging to form a rounded peak 11. A jack screw or threaded rod 12 is extended through and engages the wall of the open-

ing 2, and this screw has a head 13 at one end for engagement by a wrench.

Mounted on the screw between the crosshead 1 and the head 13 is a disc 14. That face of the disc nearest the crosshead is formed with an inwardly tapering recess 15.

Normally the arms 6 of the tool hang substantially parallel with the screw 12, as shown in Figure 1, at which time the distance between the outer ends of the lugs 7 is less than the diameter of the opening into which the tool is to be inserted.

The portion of the structure having the recess has been indicated as "S" and in this recess is seated the object to be removed. In the present instance it is a ball bearing "B."

The tool is inserted into the bearing and recess until one end of the screw engages the bottom wall of the recess. The crosshead 1 is fed along the screw by rotating the screw and crosshead relative to each other until the lugs are positioned inwardly from the bearing "B." At this time the disc 14 is fed along the screw until it comes against the inclined faces 9 of the two heads 5. Feeding of the disc will cause it to swing the cam portions 8 of the head 5 toward each other, as shown in Figure 2, and at the same time cause the lugs 7 to move outwardly into position back of the bearing "B." With the parts thus set the screw 12 is rotated so as to feed the crosshead and the disc 14 toward the head 13 and as the screw is bearing against the bottom of the recess, such rotation will result in the forcible extraction or withdrawal of the bearing.

What is claimed is:

A tool for removing rings and the like from blind holes, including a crosshead, opposed members mounted therein, each having a cam at one end and a jaw at its other end and a fulcrum supported by the crosshead and located between the cam and jaw, each jaw comprising an arm and a laterally extending lug, the lugs on the jaws being extended away from each other, a jack screw extending through and engaging a threaded opening in the crosshead between the members, said members and screw being insertible into the ring or the like to be removed, said screws being proportioned to engage and thrust against the bottom of the blind hole from which the ring or the like is to be removed, and means adjustably mounted on the screw for engaging the cams to shift the jaws apart, said means comprising a disc, there being a tapered recess in one face of the disc proportioned to receive the cams and draw them together.

CHARLES J. PIPER.
